United States Patent Office

Des. 180,463

Patented June 11, 1957

180,463

CIGAR HOLDER

Eugene H. Twarowski, Hawthorne, Calif.

Application September 28, 1956, Serial No. 43,142

Term of patent 14 years

(Cl. D85—8)

FIG. 1.

FIG. 3.

FIG. 4.

FIG. 2.

Fig. 1 is a side elevational view of a cigar holder, showing my new design, the end of a cigar being indicated in phantom lines for illustrative purposes only;

Fig. 2 is a top plan view;

Fig. 3 is a front elevational view; and
Fig. 4 is a rear elevational view thereof.

I claim:

The ornamental design for a cigar holder, as shown and described.
